UNITED STATES PATENT OFFICE.

SEWALL CABOT, OF BROOKLINE, MASSACHUSETTS.

RÖNTGEN-RAY APPARATUS.

1,095,379.

Specification of Letters Patent.

Patented May 5, 1914.

Application filed September 28, 1912. Serial No. 721,946.

To all whom it may concern:

Be it known that I, SEWALL CABOT, a citizen of the United States, and a resident of Brookline, in the county of Norfolk and State of Massachusetts, have invented a new and useful Improvement in Röntgen-Ray Apparatus, of which the following is a specification.

My invention relates to the production of Röntgen rays.

The object of my invention is to cause the tube in a condition of vacuum which will give rays of the lowest penetrating quality desired, to emit rays of any definite penetration quality desired dependent upon a definite adjustment of the apparatus for generating electrical energy and at the same time to be able to govern the quantity of rays produced to have any value desired up to the full capacity of the apparatus without any change in quality taking place caused by said change in quantity.

I have found that the penetration quality of Röntgen rays is substantially determined by the voltage maintained in the tube terminals and quantity substantially determined by the coulombs per second passing through the tube.

So far as I am aware in practically all forms of apparatus to-day used for producing Röntgen rays, current in the tube is governed by raising or lowering the terminal voltage of the apparatus. This causes a change in the penetrating quality of the ray which for reasons connected with technique in Röntgenology it is desirable to avoid.

I have found it possible to accomplish the object of my invention by using a charged condenser whose voltage is maintained at the desired value by the apparatus for generating unidirectional electrical energy and keeping this voltage fixed at any desired value. I govern the coulombs per second through the tube by varying the proportion of the total time that the tube is connected to the condenser.

My invention may best be understood by having reference to the drawing.

Figure 1 shows a front elevation of a mechanically-driven rotary switch, with certain details omitted for the sake of clearness, for

controlling the connection of the tube to the source of high potential. Fig. 2 shows in diagram details omitted from Fig. 1.

In Fig. 1 the motor M is connected to the shaft S by flexible coupling A. Rotating members C C' carried on shaft S consist of two disks of insulating material in the periphery of which are nine equally spaced conducting segments twenty degrees in length (shown in Fig. 2). These serve to intermittently connect and disconnect the circuit through pairs of brushes m_1 m_2 . . . m_{15} m_{16} and m'_1 m'_2 . . . m'_{15} m'_{16} (shown in Fig. 2). The shaft S revolves in journals B B' on which are mounted disks D D' carrying brush-holders h_1 . . . h_8 and h'_1 . . . h'_8 for the aforesaid brushes. Disk D' may be permanently secured to B'. Disk D is arranged to be rotatable on B by control handle H through angle of twenty degrees.

In Fig. 2 the condenser K is shown permanently connected to any source of high unidirectional potential having terminals x y. The double pole double throw switch F throws the circuit through the rotary switches from parallel to series when thrown from right to left and vice versa. The disks C C' may be assumed to revolve clockwise at a rate of thirty per second. In the positions indicated in Fig. 2, the disk D may be assumed to be at the counter clockwise limit of its twenty degree excursion of revolution about B. With the switch handle of F to the right under these conditions, the tube T is connected throughout the total time to condenser K through the two aforesaid rotary switches. The coulombs per second will be a maximum under this condition.

As the disk D is gradually rotated clockwise, the tube becomes intermittently connected to the condenser two hundred and seventy times per second. The percentage of total time connected gradually changes from one hundred per cent to fifty per cent at the clockwise limit of rotation of D. The switch F may then be thrown to the left and counter clockwise rotation of D will cause this percentage to vary from fifty per cent to zero per cent at the limit of counter clockwise rotation of D. This allows complete control of the number of coulombs per sec-

2
ond passing through the tube while the terminal voltage is kept at a fixed value during all the time the tube is producing rays.

I claim:

5. A system for the production of Röntgen rays comprising a source of high potential unidirectional electrical current, a Röntgen ray tube and means for connecting and disconnecting said tube to and from said source 10 simultaneously at a number of points con-

nected in series, whereby the sparking at said points is minimized.

In testimony whereof, I have hereunto subscribed my name this 17th day of September, 1912.

SEWALL CABOT.
